ATTORNEYS

UNITED STATES PATENT OFFICE.

GEORGE J. HANLON, OF NEW YORK, N. Y., ASSIGNOR OF ONE-HALF TO WILLIAM F. KURZ, OF WOODHAVEN, NEW YORK.

LIFE-SAVING DEVICE.

1,244,325.

Specification of Letters Patent. Patented Oct. 23, 1917.

Application filed May 22, 1917. Serial No. 170,176.

To all whom it may concern:

Be it known that I, GEORGE J. HANLON, a citizen of the United States, and a resident of the city of New York, Rosedale, 5 borough of Queens, in the county of Queens and State of New York, have invented a new and Improved Life-Saving Device, of which the following is a full, clear, and exact description.

10 My invention relates to devices for saving persons who have broken through ice while skating. An object of the invention is to provide a simple, inexpensive and efficient device whereby a person who has 15 broken through the ice can be saved without endangering the life of the rescuers.

With the above and other objects in view, the nature of which will more fully appear as the description proceeds, the invention 20 consists in the novel construction, combination and arrangement of parts as herein fully described, illustrated and claimed.

In the accompanying drawings, forming part of the application, similar characters 25 of reference indicate corresponding parts in all the views.

Figure 1 is a plan view of the device embodying my invention;

Fig. 2 is a side elevation of same, the 30 dotted position indicating the manner in which the device is used when a person is to be rescued;

Fig. 3 is a fragmentary longitudinal section through the device on line 3—3, Fig. 1;

35 Fig. 4 is an end elevation; and

Fig. 5 is a side elevation showing the use of the device on ice without the runners.

Referring to the drawings, 7 is a running plank formed of a pair of elongated members 8 maintained in spaced parallel relation by rungs 9 provided at suitable intervals and which support boards 10 extending longitudinally and parallelly of the side members 8. Said boards 10 are preferably 40 shorter than the side members and placed toward one end of the running plank so as to leave a clearance at the other end.

A drop ladder 11 is provided in said clearance. It is hinged to the ends of the 45 side members 8 by links 12 to swing under the rungs 9 which are in closer spaced relation at the said end of the plank. The free end of the ladder 11 is engageable by the end of a bar or rod 13 suspended from the

plank 7 by loops 14. The other end of 55 said bar carries a grab hook 15. The side members 8 at the ends remote from the drop ladder 11 terminate with handles 16.

The plank, with the drop ladder, is balanced on a standard 17 in which recesses 60 18 are formed for trunnions 19 which form an extension of one of the rungs 9. The standard 17 is provided with a suitable runner or runners 20 for facilitating the movement of the contrivance on the ice. 65

In a case where a person breaks through the ice without disappearing, the device is run up to the place of the accident and the rod 13 is pulled to release the free end of the drop ladder 11 which will swing to a 70 substantially vertical position. It is then lowered into the hole in the ice to allow the person hanging on to the ice to get a foot hold on any of the rungs of the drop ladder. The person can then be raised by see-sawing 75 the plank. It will be seen that with this device a person who has broken through the ice can be approached without any danger to the rescuers, as the operation of the device for rescuing the person takes 80 place at a considerable distance from the point of danger.

In cases where a person disappears below the ice the device is run up close to the point of danger and the drop ladder is released 85 to bring the free end thereof on to the surface of the ice. By pulling slightly on the device and raising the operating end of the plank the free end of the drop ladder will 90 swing out to form an extension of the plank. 95 When the end of the plank reaches the ice the plank is raised from the standard. The loop 14 near the handle 16 of the running plank is disengaged from the rod 13, whereby the rod 13 can be removed to one side of the plank after the end thereof near the drop ladder is pulled out from the loop 14. The plank with the ladder rests on the ice 100 and serves as a support for the rescuer while the grab hook 15 is used in the hole in the ice. The plank with the ladder can be brought, if desired, to straddle over a part of the opening without endangering the person resting thereupon, due to the large surface bridged by the plank.

105

I claim:

1. A life-saving device comprising—a running plank, a carrier detachably sup-

porting the running plank, a grab hook, and means for detachably securing the grab hook to the running plank.

2. A life-saving device comprising,—a running plank, a standard for detachably supporting the running plank, a runner associated with said standard, a grab hook, and means for detachably securing the grab hook to the plank.

10. 3. A life-saving device comprising,—a running plank, a standard for supporting the plank so that the same may be seesawed on the standard, means associated with the standard for facilitating the transportation 15 of the plank, a drop ladder at one end of the plank, and sliding means operable from the other end of the plank for retaining the drop ladder at the plank and whereby said drop ladder may be released to hang from 20 said plank substantially as and for the purpose set forth.

4. A life-saving device comprising,—a runner, a standard thereon, an elongated member mounted to seesaw on the standard, 25 a ladder pivotally secured to one end of the elongated member, and a rod operable from the other end of the elongated member for engaging said ladder when the same is at the plank, whereby said ladder is prevented from 30 swinging under the action of gravity thereupon.

5. A life-saving device comprising,—a runner, a standard thereon, a running plank seesawed on the standard, a ladder pivotally connected to the plank to swing therefrom under the action of gravity upon the ladder, and a rod mounted to slide in the plank and operable from the end remote from the ladder engaging said ladder and preventing the displacement of same under the action 40 of gravity.

6. A life-saving device comprising,—a runner, a standard thereon, a running plank seesawed on the standard and removable therefrom, a ladder pivotally connected to 45 the plank to swing therefrom, a rod, and means at the ends of the rod connecting it to the plank so that the same is free to swing, said rod adapted to engage the ladder with one end when the same is at the 50 plank, the other end of the rod being in proximity to the end of the plank remote from the ladder, the means connecting the end of the rod to the plank near the end remote from the ladder being detachable from the plank so as to allow the removal of the 55 rod from the attached means to one side of the plank after the other end of the rod has been moved out from engagement with the means connecting it to the plank in proximity of the ladder.

GEORGE J. HANLON.
